UNITED STATES PATENT OFFICE.

DAVID ZORK, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

DESIGN FOR A PHONOGRAPH-CABINET.

55,003.

Specification for Design.

Patented Apr. 27, 1920.

Application filed December 26, 1919. Serial No. 347,601. Term of patent 7 years.

To all whom it may concern:

Be it known that I, DAVID ZORK, a citizen of the United States, residing at Chicago, in the county of Cook and State of Illinois, have invented a new, original, and ornamental Design for a Phonograph-Cabinet, of which the following is a specification, reference being had to the accompanying drawing, showing a plan view of phonograph-cabinet embodying my invention.

I claim:

The ornamental design for a phonograph cabinet, as shown.

DAVID ZORK.
